PRODUCTION OF CARBOXYLIC AMIDES

Walter Reppe and Ernst Keyssner, Ludwigshafen-on-the-Rhine, Germany, assignors to I. G. Farbenindustrie Aktiengesellschaft, Frankfort-on-the-Main, Germany

No Drawing. Application June 28, 1933, Serial No. 678,056. In Germany July 6, 1932

10 Claims. (Cl. 260—124)

The present invention relates to the production of amides of higher fatty acids.

It is well known that the amides of higher fatty acids containing more than about 10 carbon atoms contrasted with the amides of lower fatty acids are only obtainable with difficulty by the action of gaseous ammonia on the fatty acids. Thus hitherto the employment of pressure with the higher fatty acids has been indispensable. Moreover, there is a danger, especially when heating for long periods of time, that the amide may be converted into the corresponding nitrile by the splitting off of water.

We have now found that amides of higher fatty acids can be obtained in good yields without the employment of pressure by passing gaseous ammonia at temperatures between the melting point of the fatty acids and 250° C. through the fused fatty acids in the presence of a solid, inorganic substance having a large superficial area which are designated in the art as surface catalysts. Said solid, inorganic substances comprise for example aluminium hydrosilicates such as bleaching earths, such as fuller's earth, silica gel, natural or artificial zeolites, porous oxides and phosphates of aluminium, thorium, tungsten, cerium, praseodymium, neodymium and lanthanum, or bauxite, active carbon and pumice which is preferably impregnated with acids, such as phosphoric, sulphuric or boric acids or acid salts, such as primary sodium or potassium sulphate. The said solid, inorganic substances are usually employed in an amount of between about 1 and about 20, preferably between about 2 and about 5, per cent by weight of the fatty acids.

The reaction may be carried out in a vertical tower, the gaseous ammonia being preferably led in at the bottom of said tower. When working with large batches of acids it is preferable to pre-heat the ammonia to about the temperature of the fused acid.

The ammonia is preferably employed in a practically dry state; when the unconsumed gas is refluxed, it is preferable to dry it before returning it into the reaction vessel, for example with calcined lime. The gas stream is usually led through the molten acids at the ratio of from 5 to 100 litres, preferably from 25 to 75 litres, per hour and per litre of acid. It is preferable to choose a high streaming velocity at the beginning

of the reaction and to lower said velocity in the proportion that less ammonia is consumed. It is preferable to work at temperatures between 150° and 180° C. When employing higher temperatures up to 300° C., the speed of formation of the amide is certainly increased, but at the same time the conversion of the amide formed into the corresponding nitrile commences, the reaction being also influenced by the period of working and the velocity of the ammonia employed.

Any aliphatic carboxylic acids of the said kind may thus be converted into amides, for example lauric, myristic, palmitic, margaric, cerotic, montanic, melissic, myricylic, oleic, elaidic, erucic, linoleic, linolenic, hydroxystearic and ricinoleic acids. Most valuable amides are obtained from stearic and oleic acid, and especially from crude fatty acids obtainable from fatty oils and fats, especially of vegetable origin, for example coconut oil fatty acids, linseed oil fatty acids, cotton seed oil fatty acids, soya bean oil fatty acids, sunflower oil fatty acids and the like.

The following examples will further illustrate the nature of this invention but the invention is not restricted to these examples. The parts are by weight.

Example 1

300 parts of stearic acid and 6 parts of granules of commercial silica gel of from 1 to 4 millimetres, diameter are heated to from 150° to 170° C. in a reaction vessel provided with an efficient stirring device and an inlet and outlet for the ammonia to be employed. While stirring well, dry gaseous ammonia is led into the melt. After about 48 hours, the fatty acid is almost completely converted into its amide. The resulting crude stearic amide may be employed as such or may be purified by working it with a solvent in which the stearic amide is soluble with difficulty, such as benzine or ligroin, whereby it is freed from small amounts of coloured impurities and any nitrile present, or by distillation in vacuo. The unabsorbed ammonia, which is withdrawn together with the water formed during the reaction may be freed from water by cooling or by treatment with water-extracting agents, and returned to the reaction vessel.

The procedure is similar with other higher fatty acids as for example coconut oil fatty acids, oleic acid, dihydroxystearic acid or the fatty

acids obtainable by splitting varieties of waxes containing esters or by the oxidation of paraffin wax.

The progressive formation of amide is evidenced by the quantity of free acid still present. Thus, in the above case of crude stearic acid, the quantity of free acid present in the reaction mixture is as follows:—

10   27 per cent after 6 hours
                      13 per cent after 12 hours
                      4.2 per cent after 24 hours
                      0.5 per cent after 48 hours

In the case of pure palmitic acid the quantity of free acid present is

15   15.9 per cent after 7 hours
                      4.4 per cent after 12 hours
                      1.0 per cent after 24 hours
                      0.2 per cent after 48 hours

Example 2

Crude ricinoleic acid, containing 62.9 per cent of free acid, is treated with gaseous ammonia in the manner described in Example 1. The quantity of free acid present is

20   6.3 per cent after 21 hours
                      2.9 per cent after 45 hours
                      0.1 per cent after 65 hours

25   The resulting salve-like products have a nitrogen content of 2.07 per cent.

What we claim is:—

30   1. The process for the production of amides of fatty acids containing more than 10 carbon atoms which comprises passing gaseous ammonia, through a melt of the fatty acids, at a temperature between the melting point of the fatty acid and about 250° C. in the presence of a surface catalyst which is distributed in said melt.

35   2. The process for the production of amides of fatty acids containing more than 10 carbon atoms which comprises passing gaseous ammonia through a melt of the fatty acids, at a temperature between about 150° and about 180° C. in the presence of a surface catalyst which is distributed in said melt.

40   3. The process for the production of amides of fatty acids containing more than 10 carbon atoms which comprises passing gaseous ammonia through a melt of the fatty acids, at a temperature between about 150° and about 180° C. in the

presence of a surface catalyst which is distributed in said melt, the unabsorbed ammonia being freed from the water formed during the reaction and repassed through the melt.

45   4. The process for the production of amides of fatty acids containing more than 10 carbon atoms which comprises passing gaseous ammonia through a melt of the fatty acids, at a temperature between the melting point of the fatty acids and about 250° C. in the presence of silica gel.

50   5. The process for the production of amides of fatty acids containing more than 10 carbon atoms which comprises passing gaseous ammonia through a melt of the fatty acids at a temperature between about 150° and about 180° C. in the presence of silica gel.

55   6. The process for the production of stearic amide which comprises passing gaseous ammonia at between about 150° and about 180° C. through a melt of stearic acid in the presence of silica gel.

60   7. The process for the production of stearic amide which comprises passing gaseous ammonia at between about 150° and about 180° C. through a melt of stearic acid in the presence of silica gel, the unabsorbed ammonia being freed from the water formed during the reaction and re-passed through the melt.

65   8. The process for the production of amides of fatty acids containing more than 10 carbon atoms which comprises passing gaseous ammonia through a melt of fatty acids obtainable from fatty oils and fats, at a temperature between about 150° and about 180° C. in the presence of a surface catalyst which is distributed in said melt.

70   9. The process for the production of amides of fatty acids containing more than 10 carbon atoms which comprises passing gaseous ammonia through a melt of fatty acids obtainable from fatty oils and fats of vegetable origin, at a temperature between about 150° and about 180° C. in the presence of a surface catalyst which is distributed in said melt.

75   10. The process for the production of amides of fatty acids containing more than 10 carbon atoms which comprises passing gaseous ammonia through a melt of coconut oil fatty acids, at a temperature between about 150° and about 180° C. in the presence of a surface catalyst which is distributed in said melt.
